UNITED STATES PATENT OFFICE

EUGENE CHISHOLM, OF LOS ANGELES, CALIFORNIA

DISPLAY CABINET

Application filed February 17, 1932. Serial No. 593,638.

This invention relates to improvements in display cabinets and has particular reference to a cabinet for displaying round articles and also for dispensing said articles.

5 The principal object of the invention is to provide means for holding the article, being dispensed, against accidental displacement.

10 A further object is to produce a device which is economical to manufacture.

A still further object is to provide means whereby gravity will effectively retain the bottom article against rolling action.

15 Other objects and advantages will be apparent during the course of the following description.

In the accompanying drawing forming a part of this specification and in which like numerals are employed to designate like parts 20 throughout the same,

Fig. 1 is a top plan view of Fig. 2 with a portion thereof broken away,

Fig. 2 is a side elevation of my device,

25 Fig. 3 is an enlarged fragmentary detail view taken on the line 3—3 of Fig. 2, and

Fig. 4 is an enlarged cross sectional view taken on the line 4—4 of Fig. 2.

In dispensing round objects, such as life-savers and the like candy confection, it has 30 been found that these articles, when confined in a vertical dispensing cabinet, roll therefrom if slightly jarred and as this is the type of cabinet which the dealer most prefers, it is an objectionable feature. Applicant 35 has perfected a dispensing cabinet wherein the bottom article is caused to roll slightly back of a center line drawn through the following articles, and as a result the article next to be dispensed is effectively held 40 through the weight of the following articles.

In the accompanying drawing wherein for the purpose of illustration is shown a preferred embodiment of my invention, the numeral 5 designates a base having a vertical shaft 6 about which my cabinet rotates. My 45 cabinet consists of plates 7 and 8 and a series of containers 9. These containers are substantially U-shaped and preferably have a transparent face as shown at 11. In order to present a neat appearance between the

series of containers, I preferably employ sliding plates 12, which plates may have advertising matter thereon if desired.

Referring now to Fig. 3 it will be noted that the distance between the back of the 55 container and the transparent face is substantially equal to that of the width of the article to be dispensed and that near the bottom of the container I have slightly curved the back portion as shown at A and I have placed a rod 13 just above the opening 14 through which the article is to be delivered, the result being that as the article, for instance the article B, reaches the position shown in Fig. 3, it will engage the rod 13 60 and as soon as the article C has been removed it will be forced rearwardly so that its center line XX is back of the center line YY the center line of the remaining articles. 65 Therefore, the weight of the articles resting upon the article to be dispensed being forward of its center line, will effectively hold the article against movement until it has been forcibly removed. Thus as each article descends in the container it will be 70 moved back of the center line of the remaining articles through the contact with the rod 13.

It will thus be seen that I have produced a device which is very simple and yet will 75 produce all the objects above set forth.

It is to be understood that the form of my invention herewith shown and described is to be taken as a preferred example of the 80 same and that various changes relative to the material, size, shape and arrangement of parts may be resorted to without departing from the spirit of the invention or the scope of the subjoined claim.

Having thus described my invention, I 85 claim:

In a dispensing cabinet, a substantially U-shaped receptacle, a face plate secured to said receptacle, the cross sectional area of 90 said receptacle between said face plate and said U-shaped member being substantially 95 the same as the article being dispensed, a discharge opening formed in the lower end of said face plate, an enlarged portion formed 100 in said receptacle at a point opposite the dis-

charge opening, and a rod positioned in said receptacle at a point adjacent and above said discharge opening whereby the article next to be dispensed is moved rearwardly in said 5 receptacle.

In testimony whereof I affix my signature.

EUGENE CHISHOLM.
